MACHINERY KEY

Raymond T. Olson, Stratford, Conn.

Application June 15, 1942, Serial No. 447,169

9 Claims. (Cl. 85—8.5)

The present invention relates to improvements in machinery keys and relates more particularly to improvements in multiple-part self-locking machinery keys for use in coupling rotary machine elements together such, for instance, as shafts and gears.

One of the objects of the present invention is to provide a superior multiple-part self-locking machinery key which combines convenience of installation and removal with capacity for holding itself against longitudinal displacement, despite vibrational tendencies of the machinery with which the key may be used.

Another object of the present invention is to provide a superior machinery key of the character referred to which will successfully resist strains tending to cause it to turn about its longitudinal axis in the complementary keyways in the two machinery elements which the key may serve to couple together.

A further object of the present invention is to provide a superior multiple-part self-locking machinery key which will effectively lock itself in place without tending to cause eccentricity between the parts which it serves to couple together.

With the above and other objects in view, as will appear to those skilled in the art from the present disclosure, this invention includes all features in the said disclosure which are set forth in the appended claims.

In the accompanying drawings, in which certain modes of carrying out the present invention are shown for illustrative purposes:

Fig. 1 is a view in end elevation of a shaft and gear shown as coupled together by a key embodying the present invention;

Fig. 2 is a broken longitudinal sectional view taken on the line 2—2 of Fig. 1;

Fig. 3 is a broken longitudinal sectional view taken on the line 3—3 of Fig. 1;

Fig. 4 is a broken transverse sectional view taken on the line 4—4 of Fig. 3;

Fig. 5 is a similar view taken on the line 5—5 of Fig. 3;

Fig. 6 is an exploded perspective view of the key-parts;

Fig. 7 is a perspective view showing a preferred mode of installing a key of the present invention in the complementary keyways of a shaft and gear;

Fig. 8 is a similar view but showing a preferred mode of removing the key;

Fig. 9 is a perspective view of an alternative form of key; and

Fig. 10 is a perspective view of still another alternative form of key.

The structure of Figs. 1 to 8 inclusive

The particular three-part self-locking machinery key herein chosen for purposes of illus-

trating the present invention in these figures, comprises complementary laterally-spaced-apart side-plates 10 and 11 and a central expanding-plate 12. Each of the side-plates 10 and 11 is preferably formed of steel and is provided at its outer end with a laterally-extending integral head 13. The central expanding-plate 12 is also preferably formed of steel and is also provided at its outer end with a laterally-projecting head 14 for purposes as will hereinafter appear.

Preferably and as shown, the head 14 of the expanding-plate or member 12 has a greater length longitudinally of the key-structure than have the heads 13—13 of the complementary side-plates or members 10 and 11. Preferably also, the expanding-plate 12 has a slightly-greater over-all length than the over-all length of the complementary side-plates 10 and 11.

The outer side-face 15 of each of the respective side-plates 10 and 11 extends in substantial parallelism with the similar side-face of the other of said side-plates, and all of the plates 10, 11 and 12 are preferably so proportioned as to provide a joint cross-sectional form which is a substantially equilateral rectangle with the exception that when designed for ordinary keyways, the combined lateral width of the three elements 10, 11 and 12, when seated in the keyways, will ordinarily have a dimension slightly exceeding the height of the members 10, 11 and 12. By way of example, a key which is nominally rated at one inch in cross-sectional form to be accommodated in opposed and aligned keyways of a shaft and gear, for instance, would be so proportioned as to assume a full one-inch circumferential dimension (dimension A of Fig. 4) while its dimension in a direction parallel with the side-faces 15—15 of the side-plates 10 and 11 (dimension B of Fig. 4) would be approximately $1/64$ of an inch scant of one inch.

In the particular embodiment shown, each of the side-plates 10 and 11 is tapered from its inner to its outer end so that the inner end of each of the said side-plates is thicker than its outer end to thereby provide an inclined inner face 16. On the other hand, the central expanding-member 12 is tapered inwardly from its outer or head end to its inner end to provide the said plate 12 with sloping outer side-faces 17 which respectively conform in taper or slope to the slope or taper of the inner faces 16—16 of the complementary side-plates 10 and 11. It is obvious that, if desired, the direction of tapers just referred to may be reversed though it is preferred that the tapers of the members 10, 11 and 12 or their equivalents be in the direction described for reasons of convenience of use.

The degree of taper of the inner-faces 16—16 of the side-plates 10 and 11 is of vital import-

inasmuch as it must not exceed $\frac{7}{16}$ of an inch per foot of length. Preferably the taper referred to is maintained at substantially $\frac{1}{16}$ inch per foot of length since such a degree of taper has been found to provide maximum resistance to the longitudinal displacement of the plates 10, 11 and 12 when subjected to severe vibration as an incident to their use in machinery.

The preferable practice in installing the three-part self-locking key shown, in the aligned and opposed keyways of two machinery parts such, for instance, as a shaft 18 and a gear 19, is to first back-out the central expanding-plate 12 with reference to the complementary side-plates 10 and 11 into substantially the relationship shown in Fig. 7. In this condition, the three plates 10, 11 and 12 may be conveniently introduced into the keyways with a relatively-free sliding fit. Before the plates 10, 11 and 12 are fully inserted into the keyways of the members 18 and 19, it is most convenient to place a stop-plate 20 or its equivalent in position to check the inward movement of the side plates 10 and 11 in a manner illustrated in Fig. 7. When the parts 10, 11 and 12 have been moved into the keyways sufficiently to engage the respective inner faces of the heads 13 of the side-plates 10 and 11 with the outer edge of the stop-plate 20, the central expanding-plate may be driven in with a hammer or its equivalent until the desired degree of tightness is achieved. Ordinarily, the expanding-plate 12 would be driven in until the inner face of its head 14 was in engagement with the stop-plate 20, but if a further degree of tightness is required, the stop-plate 20 may be removed and the expanding-plate 12 driven further in.

Since the side-faces of the keyways in the shaft 18 and gear 19 are most apt to be relatively rough, it is to be noted that in tightening the composite key in place, the sliding movement is between the relatively-smooth inner faces 16-16 of the side-plates 10 and 11 and the opposite outer faces 17-17 of the expanding-plate 12. Under most conditions, the stop-plate 20 above referred to is merely useful as a gauge in definitely positioning the side-plates 10 and 11 before the expanding-plate 12 is driven home. When the central expanding-member 12 is driven home, a uniform lateral expansion occurs throughout the length of the composite key and not only are the three plates of the key retained against longitudinal displacement with respect to each other, but the key itself and the shaft 18 and gear 19 or their equivalents, are each held against displacement with respect to each other in a direction lengthwise of the key.

When it is desired to remove the key, the stop-plate 20 or its equivalent may be placed as shown in Fig. 8, between the outer face of the gear 19 and the inner face of the head 14 of the expanding-plate 12 and thereafter the side-plates 10 and 11 may be driven inwardly by means of a drive-bar 21, which latter may be propelled by a hammer or other suitable tool, as indicated in Fig. 8. When the side-plates 10 and 11 have been driven in relatively to the central expanding-plate 12, the lateral dimensions of the composite key are thereby reduced and the entire three plates 10, 11 and 12 may be jointly withdrawn from the shaft 18 and gear 19 while in substantially the relationships shown in Fig. 8.

The structure of Fig. 9

In large size keys, instead of providing integral heads such as the heads 13 and 14 before described, I may, if desired, provide each of the three plates 10a, 11a and 12a of a self-locking key shown in Fig. 9, with heads in the form of machine screws or studs 22. Also if desired and as shown in Fig. 9, each of the three plates such as the plates 10a, 11a and 12a, may be provided with a transverse aperture 23 adjacent its outer end. All three plates may be ultimately locked together after their installation by means of a suitable transverse binding-screw such as is indicated by the broken lines 23a and extended jointly through the aligned apertures 23, 23, 23 of the respective plates.

The structure of Fig. 10

As shown in Fig. 10, a key comprising complementary side-plates 10b and 11b, as well as central expanding-plate 12b, may have each of its said side-plates provided with one of two relatively-small heads 24-24, respectively lightly welded to the outer end of each of the said side-plates 10b and 11b, so that, once they have served their purpose, they may be knocked off and discarded.

The expanding-plate 12b may be provided in its outer end with a threaded socket 25 into which may be threaded any suitable screw, such as is indicated by the broken lines 25a, to act as a hold-back in lieu of a head such as 14 or 22.

The composite key of Fig. 10 is admirably suited for use in situations where it is desired to have the outer end of the key flush or substantially flush with the outer ends of the keyways in which it may be fitted.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A multiple-part self-locking machinery key, including in combination: two complementary laterally-spaced-apart side-plates each of substantially-rectangular form in cross section and having an outer side-face extending in substantial parallelism with the outer side-face of the other side-plate and each having an inner face sloping longitudinally with respect to its outer side-face to a degree of less than $\frac{7}{16}$ " per foot of length; and an expanding-plate of substantially-rectangular form in cross section and located between the two said side-plates and having each of its respective opposite side-faces conforming in longitudinal slope to and engaging with the inner face of the adjacent one of the two said side-plates.

2. A multiple-part self-locking machinery key, including in combination: two complementary laterally-spaced-apart side-plates each of substantially-rectangular form in cross section and having an outer side-face extending in substantial parallelism with the outer side-face of the other side-plate and each having an inner face sloping longitudinally with respect to its outer side-face to a degree of less than $\frac{7}{16}$ " per foot of length, each of the said side-plates being formed adjacent its outer end with hold-back means to

limit its penetration into a keyway; and an expanding-plate of substantially-rectangular form in cross section and located between the two said side-plates and having each of its respective opposite side-faces conforming in longitudinal slope to and engaging with the inner face of the adjacent one of the two said side-plates, the said expanding-plate also being formed adjacent its outer end with hold-back means.

3. A multiple-part self-locking machinery key, including in combination: two complemental laterally-spaced-apart side-plates each of substantially-rectangular form in cross section and having an outer side-face extending in substantial parallelism with the outer side-face of the other side-plate and each having an inner face sloping longitudinally with respect to its outer side-face to a degree of less than $\frac{7}{64}$ " per foot of length, each of the said side-plates being formed with a laterally-projecting hold-back head; and an expanding-plate of substantially-rectangular form in cross section and located between the two said side-plates and having each of its respective opposite side-faces conforming in longitudinal slope to and engaging with the inner face of the adjacent one of the two said side-plates, the said expanding-plate being provided with a laterally-projecting hold-back head.

4. A multiple-part self-locking machinery key, including in combination: two complemental laterally-spaced-apart side-plates each of substantially-rectangular form in cross section and having an outer side-face extending in substantial parallelism with the outer side-face of the other side-plate and each having an inner face sloping longitudinally with respect to its outer side-face to a degree of less than $\frac{7}{64}$ " per foot of length, each of the said side-plates being provided with a laterally-projecting hold-back stud to limit its penetration into a keyway; and an expanding-plate of substantially-rectangular form in cross section and located between the two said side-plates having each of its respective opposite side-faces conforming in longitudinal slope to and engaging with the inner face of the adjacent one of the two said side-plates, the said expanding-plate being provided with a laterally-projecting hold-back stud.

5. A multiple-part self-locking machinery key, including in combination: two complemental laterally-spaced-apart side-plates each of substantially-rectangular form in cross section and having an outer side-face extending in substantial parallelism with the outer side-face of the other side-plate and each having an inner face sloping longitudinally with respect to its outer side-face to a degree of less than $\frac{7}{64}$ " per foot of length; and an expanding-plate of substantially-rectangular form in cross section and located between the two said side-plates and having each of its respective opposite side-faces conforming in longitudinal slope to and engaging with the inner face of the adjacent one of the two said side-plates, the said expanding-plate being formed in its outer end with a threaded socket for the reception of a hold-back screw.

6. A multiple-part self-locking machinery key, including in combination: two complemental laterally-spaced-apart side-plates each of substantially-rectangular form in cross section and having an outer side-face extending in substantial parallelism with the outer side-face of the other side-plate and each having an inner face sloping

longitudinally with respect to its outer side-face to a degree of less than $\frac{7}{64}$ " per foot of length; and an expanding-plate of substantially-rectangular form in cross section and located between the two said side-plates and having each of its respective opposite side-faces conforming in longitudinal slope to and engaging with the inner face of the adjacent one of the two said side-plates; each of the two said side-plates and the said expanding-plate being formed with a transverse aperture positioned to align with the apertures in the remaining plate when the key is seated in the keyways of machinery parts.

7. A multiple-part self-locking machinery key, including in combination: two complemental laterally-spaced-apart side-plates each of substantially-rectangular form in cross section and having an outer face extending in substantial parallelism with the outer side-face of the other side-plate and each having a sloping inner face diverging from its outer side-face progressively from its outer to its inner end to a degree of less than $\frac{7}{64}$ " per foot of length; and an expanding-plate of substantially-rectangular form in cross section and thicker at its outer end than at its inner end and located between the two said side-plates and having each of its respective opposite side-faces conforming in longitudinal slope to and engaging with the inner face of the adjacent one of the two said side-plates.

8. A multiple-part self-locking machinery key, including in combination: two complemental laterally-spaced-apart side-plates each of substantially-rectangular form in cross section and having an outer side-face extending in substantial parallelism with the outer side-face of the other side-plate and each being thicker at its inner end than at its outer end, each of the said side-plates having an inner face sloping longitudinally with respect to its outer side-face to a degree of less than $\frac{7}{64}$ " per foot of length, and each of the said side-plates being formed with hold-back means to limit its penetration into a keyway; and an expanding-plate of substantially-rectangular form in cross section and thicker at its outer end than at its inner end and located between the two said side-plates and having each of its respective opposite side-faces conforming in longitudinal slope to and engaging with the inner face of the adjacent one of the two said side-plates.

9. A multiple-part self-locking machinery key, including in combination: two complemental laterally-spaced-apart side-plates each of substantially-rectangular form in cross section and having an outer side-face extending in substantial parallelism with the outer side-face of the other side-plate and each being thicker at its inner end than at its outer end, each of the said side-plates having an inner face sloping longitudinally with respect to its outer side-face to a degree of less than $\frac{7}{64}$ " per foot of length, each of the said side-plates being formed with a laterally-projecting integral hold-back head to limit its penetration into a keyway; and an expanding-plate of substantially-rectangular form in cross section and thicker at its outer end than at its inner end and located between the two said side-plates and having each of its respective opposite side-faces conforming in longitudinal slope to and engaging with the inner face of the adjacent one of the two said side-plates.
